UNITED STATES PATENT OFFICE.

WILLIAM A. JAMES, OF MILWAUKEE, WISCONSIN, ASSIGNOR OF ONE-FOURTH
TO THE WILKIN MANUFACTURING COMPANY, OF SAME PLACE.

SKIM-GATE FOR MOLDS.

SPECIFICATION forming part of Letters Patent No. 508,884, dated November 14, 1893.

Application filed November 17, 1890. Serial No. 371,665. (No model.)

To all whom it may concern:

Be it known that I, WILLIAM A. JAMES, of Milwaukee, in the county of Milwaukee, and in the State of Wisconsin, have invented certain new and useful Improvements in Skim-Gates for Molds; and I do hereby declare that the following is a full, clear, and exact description thereof.

My invention relates to molds used in making castings of various kinds, and my invention consists in certain peculiar and novel features of construction and arrangement as hereinafter described and pointed out in the appended claims.

15 In order that my invention may be fully understood, I will proceed to describe it with reference to the accompanying drawings, in which—

Figure 1 is a sectional view of a mold with 20 my improved skim-gate applied thereto. Fig. 2 is a transverse vertical section of the same on the line 2—2 of Fig. 1.

Previous to my present invention great difficulty has been experienced in making perfect castings on account of the entrance of 25 slag or dross into the matrix of the mold.

Although skimmers have been used in connection with the pouring ladles, they are not wholly effective in operation, even where the 30 utmost care is taken, and consequently much slag or dross enters the mold and runs into the matrix and thus greatly lowers the quality of the casting.

It is the object of my invention to entirely 35 exclude dross or slag from the matrix and thus produce perfectly homogeneous castings. This result I accomplish by virtue of the construction and in the manner which I will now proceed to describe.

40 Referring to the drawings A designates the drag, and B the cope of a molder's flask.

C designates the parting between the sand c in the drag and the sand c' in the cope, and D designates the matrix of the mold, which 45 imparts the required form to the casting.

E designates the cast-gate or ingate which extends downward through the sand in the cope and also partially into the sand in the drag and the lower extremity of which 50 communicates with one end of a channel f with which my improved skim-gate F is provided.

The opposite end of this channel f communicates with the upper end of an auxiliary cast-gate or ingate E' which is of L-form and is also formed in the sand of the drag. The opposite end of gate E' communicates with the lower end of a channel d the upper end of which communicates with one end of the matrix D.

The skim-gate F preferably of the form 60 shown, is formed from clay or other suitable material, being shaped as a core box and baked in the ordinary manner. This skim gate is provided on the upper side of its bottom with transverse ribs f' and above and 65 alternately between the ribs f' with other transverse ribs f"; openings f' being thus left in the upper side of the gate intermediate of the ribs f". Thus the channel is composed of a succession of inverted and upright U-shaped continuous sections; the tops of the inverted sections being open, and the bottoms of the alternate sections being closed. A number of recesses G, preferably of approximately conical shape are formed in the 70 sand in the cope and register with the openings f' in the top of the skim-gate F; the said recesses being formed by correspondingly shaped blocks (not shown) which are removed 75 previous to the molding operation.

80 From the above description it will be seen that when the metal is poured into the cast-gate or ingate E, it will flow down therein and enter the channel f of the skim-gate F. In flowing through this gate the ribs f', f" thereof will cause the metal to flow alternately upward and downward and the slag or dross, being of less specific gravity than the metal, will collect within the recesses G and thus be retained by the latter. The pure metal will 85 flow into the auxiliary gate or channel E' and finally enter the matrix where it will cool and solidify in the form of a perfectly homogeneous casting.

90 The above described form of skim gate is 95 designed more particularly to be located at the point of separation between the drag and the cope of the flask, but when it is desired to make very heavy or deep castings, the skim gate may be made of greater thickness, 100 and the upper ribs f" extended to the top thereof so as to form chambers between said

ribs for the accumulation of the dross and slag. The skim gate is located, in this instance, entirely below the joint between the drag and the cope, and a covering is placed over the upper openings to prevent the entrance of sand to the interior of said skim gate, the recesses G, being dispensed with by reason of the increased size of the upper openings in said skim gate, and the sand is firmly rammed into the drag upon all sides of the skim gate, the ingate being arranged to communicate with one end of the latter, and the other end of said skim gate being arranged in communication with the auxiliary ingate, as before described.

While I have described my invention as applied to flask molds it is obvious that it is equally applicable to other forms of molds without impairing its efficiency.

Having thus described my invention, what I claim as new therein, and desire to secure by Letters Patent, is—

1. A skim gate for molders' use comprising a hollow body of baked clay or analogous material provided with a longitudinal channel having openings at opposite ends of said body adjacent to the bottom thereof and

with transverse ribs extending alternately from the upper and the lower surfaces of said longitudinal passage, and recesses located in the top of said body adapted to collect the dross and slag and prevent the same from passing into the matrix of the mold, substantially as described.

2. An improved skim gate for molders' use, comprising a hollow body provided with a longitudinal zig zag channel extending through the same, and having openings at opposite ends of said body adjacent to the bottom thereof of openings in the top of said hollow body, and chambers or recesses located above said openings, and adapted to collect the dross and slag and prevent the passage of the same to the matrix of the mold, substantially as described.

In testimony that I claim the foregoing I have hereunto set my hand at Milwaukee, in the county of Milwaukee and State of Wisconsin, in the presence of two witnesses.

WILLIAM A. JAMES.
